UNITED STATES PATENT OFFICE.

JAY BROWNLEE DAVIDSON AND EDGAR V. COLLINS, OF AMES, IOWA, ASSIGNEES TO
IOWA STATE COLLEGE OF AGRICULTURE AND MECHANIC ARTS, OF AMES, IOWA,
A CORPORATION OF IOWA.

DYNAMOMETER.

Application filed June 16, 1924. Serial No. 720,363.

The object of our invention is to provide a dynamometer of simple, durable and inexpensive construction for testing in a convenient, facile and economical manner the amount of power that is being generated by any prime mover, such for instance as an internal combustion engine, which applies its power through a rotary movement such for instance as by means of a pulley. Our invention consists in the construction, arrangement and combination of the various parts of the device, whereby the objects contemplated are attained, as hereinafter more fully set forth, pointed out in our claims, and illustrated in the accompanying drawings, in which:

Figure 1 shows a top or plan view of a dynamometer embodying our invention.

Figure 2 shows a vertical, sectional view of same on the line 2—2 of Figure 1, with the weights partly elevated and the valve slightly open as in use under certain conditions.

Figure 3 shows a horizontal, sectional view on the line 3—3 of Figure 2.

Figure 4 shows a vertical, sectional view on the line 4—4 of Figure 1; and

Figure 5 shows a vertical sectional view of the valve device in its fully opened position.

Referring to the accompanying drawings, we have used the reference numeral 10 to indicate the tank or receptacle in which the dynamometer is mounted. Resting on the bottom of the tank are the supporting legs 11 fixed in position by the bolts 12.

The dynamometer casing is indicated generally by the reference numeral 13. This casing is tiltingly supported by means of the trunnions 14 projected outwardly from it and mounted for rocking movement upon the upper ends of the legs 11. Within the casing there is a chamber 15 having the usual contour of a rotary pump, and adjacent to the rotary pump chamber is a second chamber in which there is rotatively mounted two intermeshing cog wheels 16. Within the chamber 15 there are two coacting rotary impellers 17, one of which is mounted upon the driven shaft 18 which is also fixed to the adjacent one of the cog wheels 16, and the other is mounted upon the driving shaft 19 which is also fixed to the other of the cog

wheels 16 and has one end extended through one of the trunnions 14 and projected to a point beyond the tank 10, a pulley 20 being fixed to its outer end.

Communicating with the interior of the chamber 15 is an intake port device 21 arranged to discharge in a radial direction toward the center of the shaft 19. Leading from the upper portion of the chamber 15 is a discharge port device 22 which is provided at its outer end with a vertically arranged cylindrical valve member 23 open at both ends. Mounted in the valve member 23 is a coacting valve member 24 capable of vertical movement, closed at its upper end and open at its lower end and provided near its central portion with a series of perforations 25 those near the upper end preferably being smaller than the ones below. Pivoted to the lower end of the valve member 24 is a link 26 extended downwardly and pivoted in turn to a support 26^a secured to the bottom of the tank 10.

Fixed to the casing 13 at the end opposite from the valve member is a beam 27 which extends through the tank 10 and is provided at its outer end with an arcuate head 27^a. Fixed to the top of this arcuate head is a flexible rod 27^b and attached to the lower end of the rod 27^b is a rod 28 upon which a weight 29 is mounted. The tank is partly filled with liquid 30, as shown in Figure 2.

In practical operation and assuming that it is desired to ascertain the maximum pulling power of a prime mover such for instance as an internal combustion engine, then the prime mover is belted to the pulley 20 and started in such a direction that the impellers 17 will move in the direction indicated by the arrows in Figure 2. Before the power is applied to the pulley 20, the weight 29 will be at its lower limit of movement and the valve device will be in the position shown in Figure 4. That is to say, it will be closed. When in this position, the impellers will be locked against rotation by the liquid contained within the chamber 15, and hence since the impellers cannot rotate when in this position, the power applied to the pulley 20 will first be utilized in tilting the casing 13. This tilting movement will be opposed by the weight 29, and

hence the device will not tilt until the torque applied to the pulley 20 is sufficient to impart such tilting movement to the casing 13 as to elevate the weight 29.

When the weight commences to elevate, the valve device will first assume a partially opened position, as shown in Figure 2, and when this position is reached, then the impellers may rotate in unison with the pulley 20, and a current of liquid will be discharged through the valve into the tank and from the tank into the rotary pump chamber 15. As the torque applied to the pulley 20 is increased, the weights will be elevated and the valve device more widely opened, as shown in Figure 5. Obviously, as the valve device approaches its wide open position, less resistance is applied by the impellers to the casing 13, in a direction tending to open the valve, and hence the gravity pull of the weights will tend to partially close the valve device.

During the continued operation of the prime mover at a certain speed, a balanced position will be established between these two opposing forces, and when this balance has been effected, the pulling power of the prime mover may be accurately determined by the amount of the weight. If the test is being made when the prime mover is running at a relatively high speed, the device will be tilted to position for opening the valve device relatively wide, and when the test is being applied to a prime mover running at a relatively low speed, the valve device will automatically remain in a relatively restricted position.

In making a test of this character, and in the event it is desired to determine the pulling power of the prime mover, when operating as distinguished from its pulling power at the start, then the operator may simply elevate the weight beam until the desired speed has been attained.

By having the intake port device arranged radially relative to the drive shaft, the impact of incoming currents of liquid is neutralized and has no tendency to tilt the casing in either direction. By having an arc on the end of the weight beam 27 arranged concentric to the driving shaft, and by having the weight supported by a flexible rod engaging the arcuate head of the beam it is obvious that the gravity pull of the weights attached to its outer end will be substantially the same when the beam is in any of its various positions of movement.

By having the casing provided with trunnions and mounted in suitable bearings, the friction caused by its tilting movements is reduced to a negligible quantity for the purpose intended, and by having the driving shaft mounted in the casing and arranged to rotate in the direction shown, any friction between the drive shaft and its bearing will

be applied to the tilting casing in the proper direction, and will not tend to alter or affect the accuracy of the test being made.

The device will not be affected by heat generated by its operation, because of the constant flowing liquid traveling through it when being operated will tend to keep it cool.

The normal amount of leakage between the impeller and the interior of the casing will not affect the accuracy of the test.

From the foregoing it will be obvious that during the operation of our improved dynamometer, torsional resistance is automatically maintained regardless of the speed of rotation, and that resistance may be varied through a wide range at the will of the operator, by attaching or removing weights.

Furthermore, extreme accuracy in the test is secured, because the balancing is automatic and the frictional loss is negligible.

The liquid within the pump casing, when acted upon by the impeller contained within the casing, provides means for opening the valve on account of its action tending to tilt the casing when the valve is closed, or partly closed.

The beam and weight constitute a resistance device operatively connected to the valve device for opposing the opening movement of the valve device. Obviously a spring may be substituted in place of the weight.

We claim as our invention:

1. In a dynamometer, the combination of a tilttable casing, an impeller device therein so arranged that liquid will be positively driven thereby through the casing when the impeller device is rotated, means for rotating the impeller device, a yielding pressure device applied to the casing for tilting it in one direction, and a valve device for controlling the passage of liquid through the casing, one member of the valve device being connected to the casing and the other member being connected to a stationary support, said valve device being so arranged and combined that when the casing is tilted in the direction opposing the force exerted by the yielding pressure device, the valve will be opened, and when the casing is tilted in the opposite direction the valve will be closed.

2. In a dynamometer, the combination of a tilttable casing, an impeller device therein so arranged that liquid will be positively driven thereby through the casing when the impeller device is rotated, means for rotating the impeller device, a yieldable pressure device applied to the casing for tilting it in one direction, and a valve device for controlling the passage of liquid through the casing, said valve device comprising a valve member fixed to the casing and communicating with the interior of the casing, a sliding member so arranged that in one direction it will close the passage from the casing, and

in its other position it will permit the contents of the casing to pass out through the valve, and a link connected to said sliding valve member and to a stationary support.

- 5 3. A dynamometer, comprising a tank for containing liquid, bearings mounted in the tank, a casing formed with trunnions tiltably mounted in said bearings, a driving shaft extended through the casing concentric 10 with said trunnions, an impeller device within the casing comprising a driving impeller member and a driven impeller member, said casing being formed with an intake passageway arranged radially to the driving shaft, 15 said casing also being formed with a discharge passageway having at its outer end an upright tubular valve member, a coacting tubular valve member slidably mounted

therein open at its bottom and formed with a series of openings of different sizes formed 20 in the side walls of the said sliding valve member so positioned that one or more of them may communicate with the said discharge passageway from the casing depending on the position of the sliding valve member within the upright tubular valve member, a link pivotally connected to the said sliding valve member and extended downwardly and connected to a stationary support, and a beam fixed to the casing and extended in a direction radial to the driving shaft, and a weight device on said beam, substantially as and for the purposes stated. 25 30
